UNITED STATES PATENT OFFICE.

CHARLES P. MILLS, OF PITTSBURGH, PENNSYLVANIA, ASSIGNOR TO THE DURALOY COMPANY, OF PITTSBURGH, PENNSYLVANIA, A CORPORATION OF DELAWARE.

BAFFLE FOR BOILERS, STILLs, AND THE LIKE.

Application filed March 15, 1927. Serial No. 175,520.

In the case of modern boilers, stills and the like, means are employed to prolong the play of the flames and burning gases from the fuel over the boiler tubes, such means comprising walls called "baffles", and which are assembled of refractory units such as terra cotta tile or fire brick. Such refractory walls are supported either by the tubes themselves or by being arched between the side walls of the furnace.

These refractory baffles are characterized by a number of weaknesses which impair their efficiency, cause them to require relatively frequent repairs and shorten their lives.

The changes of furnace temperature, due to varying fire conditions or the placing the boiler into and taking it out of service, cause alternate expansion and contraction of the relatively non-elastic refractory units, producing leaks and holes in the baffles which act to by-pass more or less of the heat currents, thus interfering with or destroying the intended flow so that portions of the tubes are no longer exposed to the full or effective heating effect. Such expansion and contraction also serve to disintegrate the individual units. The impingement of the burning gases on the refractory units, which are not of uniform composition, also causes such units to disintegrate and drop out of place. Where the refractory baffles are supported on inclined tubes, such baffles become loosened under service conditions and shift or creep from their proper places.

Where the fuel used is gas, either natural or producer, the flames tend to throb, and due to imperfect mixture sub-explosions occur beyond the primary combustion chamber. Such throbbing and explosions tend to loosen and break up the baffle.

Again, the weight of the refractory walls is considerable and consequently the tubes which support the same tend to bend and become leaky.

In the case of baffles assembled of refractory units and supported by the tubes, the units are laid on the tubes and thus portions of the surfaces of the latter are masked

from the currents of burning gases and the flames, thus causing a loss in effective heating area.

The material cost of such baffles is not great compared to the excessive labor cost of installing and the time lost incident to the installing, repairing and replacing.

Unless the baffles are kept substantially gas-tight, short circuits in the flow of burning gases are produced which seriously impair the heat application to the tubes and thus materially reduce the efficiency of the boiler, still or the like.

Again, the refractory units or fragments of the same frequently drop down from the baffles onto the mechanical stokers, causing serious injury to the latter.

The object which I have in view is the provision of baffles for boilers, stills and the like, which may be quickly installed, removed and repaired; which will not be subject to the injurious effects of expansion and contraction, nor destroyed or rendered leaky in service; which will at all times maintain the desired travel of the burning gases, and which will not mask the tubes from the burning gases nor cause the same to become bent nor leaky.

For this purpose I employ baffles comprised of rolled metal plates supported by and in spaced relation to the tubes, and which are too light in gauge to overload the tubes or to be materially distorted or affected by expansion and contraction.

The plates which form a baffle are assembled with sealed joints which prevent leakage, and the plates are so anchored in position as to prevent baffle creeping or displacement.

The joints are also arranged to permit the individual plates to expand and contract without accumulating the expansion or contraction over the baffle as a whole.

The baffles may be quickly and easily repaired by the removal and replacement of individual plates when required.

The plates are rolled from suitable steel. For use in the presence of temperatures not to exceed 900 degrees Fahr. steel or iron may

be employed, but for higher temperatures I use a suitable heat-resistant steel or iron alloy which is unaffected by repeated changes of temperature.

5 The alloy which I prefer to use is a chrome or chrome-nickel alloy, the percentage of the chrome or chrome and nickel being varied in accordance with the temperatures to which the baffles are to be exposed.

10 Again I may employ steel or iron plates which are plated with an alloy such as chrome, as by the electro-plating method.

I provide new and improved means for supporting or anchoring my improved baffles 15 in place whereby the baffles are held in position against accidental displacement, the plates are permitted to independently expand and contract, and the supporting tubes are not masked from the currents of burning 20 gases.

Other novel features of construction and arrangement of parts will appear from the following description.

In the accompanying drawings, wherein I 25 have illustrated the best embodiment of the principles of my invention now known to me, Fig. 1 is a side elevation of the tubes, mud drum and headers of a boiler of the "Stirling" type which is characterized by 30 the provision of a mud drum connected by three banks of tubes to three elevated headers; Fig. 2 is a side view showing the method of assembling the baffle plates and mounting them on the tubes; Fig. 3 is a 35 section taken along the line III—III in Fig. 2; Fig. 4 is a view similar to Fig. 2 showing a modification; Fig. 5 is an enlarged detail of one of the baffles shown in Fig. 1; Fig. 6 is a view similar to Fig. 1 40 but showing a boiler of the "Ladd" type wherein the mud drum is connected to a single elevated header by three banks of tubes; Fig. 7 is a similar view of a boiler of the "Parker" type in which the tubes are 45 horizontally disposed; Fig. 8 is a similar view of a boiler of the "Union Iron Works" type in which the mud drum is connected by banks of tubes with the three headers and the headers are also connected by tubes; Fig. 50 9 is an enlarged detail of one of the baffles shown in Fig. 8; Fig. 10 is a sectional view taken along the line X—X in Fig. 9; Fig. 11 is an elevation of a baffle positioned between widely spaced apart banks of tubes; 55 Fig. 12 is an enlarged section taken along the line XII—XII in Fig. 11; Fig. 13 is a detail in plan showing the overlapping ends of two baffle plates with their bolt holes arranged to permit the plates to expand and contract individually, and Fig. 14 is a sectional view taken along the line XIV—XIV 60 in Fig. 13.

Referring first to Figs. 1, 2 and 3, 1 represents the banks of tubes which connect the

6 mud drum 2 with the headers 3, 4 and 5. 6 65 represents tubes connecting the headers. 7 represents the bridge wall and 8 the front and rear walls of the boiler furnace.

9, 10, 11, 12, 13, 14 and 15 represent plate-metal baffles which are mounted on the tubes 70 in the proper positions to obtain the desired travel of the burning gases relative to the tubes.

In the case of the baffles 9, 10, 11, 12, 13 75 and 14, the same are formed by assembling the plates together and mounting them on the tubes in substantially the manner shown in Figs. 2 and 3 wherein 16, 17 and 18 represent three plates which are united in sealed relation and secured to the tubes, 80 one of which is indicated at 19.

The specific disclosure for assembling the plates and for attaching them in place is as follows.

20 represents saddle blocks having one 85 face, the lower in Figs. 2 and 3, provided with a substantially semi-circular or arcuate recess 21 which fits around the tube 19. 90 22 is a U-bolt whose curved bridge portion completes with the recess 21 the encirclement of the tube 19, the legs of the bolt 22 extending through parallel bolt holes in the block 20 and having nuts 23 screwed up thereon against the surface of the block, thus fixedly, yet detachably, securing the 95 blocks in place on the tubes.

24 represents cleats having spaced apart 100 holes by means of which said cleats may be slipped on over the ends of the bolt 22. The ends of the adjacent baffle plates are 105 punched to provide bolt holes and are placed in overlapping relation with the bolt holes in registration and engaged by the legs of the U-bolts 22. The exterior cleats 25 are then put in place on the bolts and the nuts 26 applied and tightened on the bolts, thus securing the plates in assembled 110 relation. A row of spaced apart saddle blocks and U-bolts are provided at the proper interval along the overlapping edges of adjacent sheets. Thus the same 115 may be positioned on say twelve inch centers.

The bolt holes in the baffle plates are sufficiently large in diameter relative to the U-bolts, or they may be slotted longitudinally 115 of the baffle plates as indicated in Figs. 13 and 14, to permit the plates to expand and contract independently of each other so that there is no accumulation of expansion and contraction in the baffle wall as a whole.

The usual clearance of a sixteenth of an 120 inch in the bolt holes is generally sufficient, but is preferable to elongate the bolt holes in the baffle plates to provide ample clearance.

In Fig. 4 I show the plates bolted to the saddle blocks without the use of cleats. This enables me to bring the baffle closer to

the tubes from which it is supported where it is desirable.

I prefer to centrally recess, as at 27, the portion of the saddle blocks against which the plates are bolted, leaving two spaced apart, flat topped abutments 28 against which the cleats or plates bear. This not only results in a saving of metal but it also lessens the areas in surface contact and thus 10 reduces the frictional resistance as the plates expand and contract. The use of the cleats 24 and 25 also reduces the frictional resistance to the movement of the material of the plates in expansion and contraction.

15 The ends of the plates extend to and may abut against or be embedded in the side walls of the furnace.

The plates are rolled in relative narrow width, preferably of about eighteen inches, 20 and this facilitates changes in direction of the baffle formed of said plates. Such changes of direction may be accomplished by bending one or more of the plates as in the case of the baffle 14 in Fig. 1.

25 It will be noted that the relative narrow width of the baffle in the direction of the length of the tubes permits the plates to expand and contract independently of each other without accumulating the total expansion or contraction over the baffle as a 30 whole and without a thrust on the saddle blocks which might cause the same to shift along the tubes. Thus creeping of the baffle relative to the tubes upon which it is supported is avoided. Again the relative narrowness of the plates of which the baffle is assembled minimizes the warping effect of 35 the uneven heating of the large area of the baffle.

40 Where the temperatures to which the baffles are subjected do not exceed 900 degrees Fahr. rolled steel or iron plates may be employed. Where the temperatures are higher, I employ alloy steel or iron, preferably a 45 chrome or chrome-nickel alloy. Thus for temperatures between 900 and 1400 degrees Fahr. I may employ a low alloy steel or iron containing from 12% to 14% of chrome, or chrome and nickel in the proportion of 50 about 5% of one to 10% or 12% of the other. For use in the presence of temperatures of from 1400 to 2300 degrees Fahr. an alloy containing a higher percentage of 55 chrome or chrome and nickel should be used, such as 24% to 35% of the chrome alone, or chrome and nickel in the proportion of 25% of one and 10% of the other.

Again I may employ steel or iron plates plated, as by the electro-plating method, 60 with a suitable heat-resisting alloy, such as chrome.

The cleats are of similar material to the plates.

I prefer to use plates rolled to not more

than one-eighth inch in thickness. However, under similar heat conditions the plates of steel alloy or iron alloy may be of less thickness than a plate of steel or iron.

The pillow blocks are castings which should be of alloy steel or iron where the 70 temperature requires.

In Fig. 5 I have illustrated in detail the baffle 15 shown in Fig. 1 as a single plate spanning the relatively narrow space between the left hand and the intermediate 75 banks of tubes. Thus at its outer or left hand edge said plate is bolted to an angle iron 29 which in turn is secured to the tubes by the U-bolts of the pillow blocks. The other or right hand edge of the plate 15 is 80 bent upwardly at the proper angle to fit in flat surface contact against the adjacent plate of the baffle 10, the U-bolts of the saddle blocks of the baffle 10 extending through the plate 15 with the nuts screwed 85 up against said plate.

It is evident that with the proper looseness in the fit of the bolt holes in the plate 15 its expansion or contraction would not exert a thrust on the tubes.

90 In Fig. 6, illustrating the application of my invention to a Ladd boiler, the banks of tubes 1 which connect the mud drum 2 with the single header 3 are provided with the baffles 30, 31 and 32 likewise comprised of 95 plates assembled and attached to the tubes by saddle blocks and U-bolts. In this case the top plate of the baffle 31 is shown bent over and flanged upwardly as at 33 to be secured by the U-bolts of the baffle 30.

100 In Fig. 7, illustrating the application of my invention to a Parker type of boiler, the baffles 34, 35, 36 and 37 are horizontally disposed, as are the tubes 1, the front end of the lowermost baffle being bolted to the front 105 wall 38 of the fire box.

110 In Fig. 8, illustrating the application of my invention to the Union Iron Works type of boiler wherein the banks of tubes connect the mud drum 2 with the headers 3, 4 and 5 and the tubes 6 connect the headers 3 and 4, the baffles 39, 40, 41, 42 and 42^a are 115 substantially like the baffles 9, 10, 11 and 12 in Fig. 1, while the baffle 43 is substantially like the baffle 15 in Figs. 1 and 5. 45 represents the tube sheet.

46 represents a baffle which spans the space between two banks of tubes and also extends inside one of the banks, the intermediate bank in Fig. 8, to connect with the 120 baffle 40. The construction of the baffle 46 is shown in detail in Figs. 9 and 10. The side of the plate is slotted as at 47 to provide clearance for the outer row of tubes of the intermediate bank and the ends of the 125 tongues 48 thus formed are bent upwardly to fit flat against and to be bolted as at 49 to the baffle 40. The bolt holes in the plate

46 are given sufficient clearance to permit the plate to expand and contract independently.

50 in Fig. 8 represents a baffle spanning 5 the space between relatively widely separated banks of tubes, the space to be filled being too great to be spanned by the width of a single baffle plate. The construction of 10 the baffle 50 is shown in detail in Figs. 11 15 and 12, being comprised of a plurality of plates such as 50^a, 50^b, 50^c and 50^d disposed lengthwise between the banks of tubes with 20 their lateral edges overlapping and bolted together as at 51. The upper end of every 25 other plate is flanged, as at 52, so as to be engaged by the U-bolts 22 of the saddle blocks 20 mounted on the upper bank of tubes. The lower ends of the plates are 30 bolted to an angle bar 53 which is secured 35 to the upper banks of tubes by the saddle blocks and U-bolts of the baffle 42^a.

With proper clearance in the bolt holes of the plates it is evident that they may individually expand or contract without causing 25 the baffle to creep, buckle or exert a thrust on the tubes.

30 My improved baffles are light in weight and do not distort the tubes nor cause leakage. The ease with which my baffle may be installed and maintained enables me to position them in the boiler or still in just the proper position to obtain the best possible 35 flow of the flaming gases.

35 The saddle blocks support the baffles in spaced relation to the tubes so that no portions of the tubes are masked but the entire surface areas of the tubes are exposed to the full heating effect.

40 It is thus evident that my improved baffles are not only cheaper to install and keep in repair, but are also more efficient than the baffles now in general use in boilers, stills and the like.

45 What I desire to claim is:—

1. A baffle between adjacent banks of 50 tubes of tubular boilers, stills and the like, comprising a metal plate, saddle blocks clamped to the tubes of both banks, and means for securing the ends of the plate 55 to said saddle blocks, said means including provision for the individual expansion and contraction of the plate independently of the saddle blocks.

2. A baffle between spaced apart banks of 60 tubes in tubular boilers, stills and the like, comprised of a plurality of relatively narrow metal plates disposed longitudinally to span the space between the banks and having their lateral edges in sealed relation together to form a continuous baffle, and means for attaching the ends of said plates to the tubes of the two banks.

3. A baffle between spaced apart banks of 65 tubes in tubular boilers, stills and the like

comprised of a plurality of relatively narrow metal plates disposed longitudinally to span the space between the banks and having their lateral edges in sealed relation, and means for attaching the ends of said plates to the tubes of the two banks, said plates being free to expand and contract independently of their attachment to the tubes. 70

4. A baffle between spaced apart banks of 75 tubes in tubular boilers, stills and the like comprised of a plurality of relatively narrow metal plates disposed longitudinally to span the space between the banks and having their lateral edges in overlapping relation with each other to form a continuous baffle, and means for attaching the ends 80 of the plates to the tubes of the two banks.

5. A baffle between spaced apart banks of 85 tubes in tubular boilers, stills and the like comprised of a plurality of relatively narrow metal plates disposed longitudinally to span the space between the banks and having their lateral edges in overlapping relation, and means for attaching the ends of the plates to the tubes of the two banks, said plates being free to expand and contract 90 independently of their attachment to the tubes.

6. A baffle between spaced apart banks of 95 tubes in tubular boilers, stills and the like comprised of a plurality of relatively narrow metal plates disposed longitudinally to span the space between the banks and having their lateral edges in overlapping relation, and means for attaching the ends of the plates to the tubes of the two banks, 100 said plates being free to expand and contract independently of each other and of their attachment to the tubes.

7. A baffle for tubular boilers, stills and the like comprised of a plurality of metal 105 plates assembled with sealed edges, saddle blocks spaced along the tubes and having arcuate recesses engaging the walls of the tubes and U-bolts having their loops engaging the tubes and extending through 110 holes in the saddle blocks and in the plates to clamp the saddle blocks to the tubes and the plates to the saddle blocks.

8. A baffle for tubular boilers, stills and the like comprised of a plurality of metal 115 plates assembled with sealed edges, saddle blocks spaced along the tubes and having arcuate recesses engaging the walls of the tubes and U-bolts having their loops engaging the tubes and extending through holes 120 in the saddle blocks and in the plates to clamp the saddle blocks to the tubes and the plates to the saddle blocks, said saddle blocks holding the plates in spaced relation to the tubes.

9. A baffle for tubular boilers, stills and the like comprising a plurality of relatively narrow metal plates disposed in a plane sub- 125

stantially parallel to that of the tubes and having their lateral edge portions in contact with each other to form a continuous baffle, saddle blocks mounted on the tubes, 5 means for anchoring the saddle blocks fixedly to the tubes and means for attaching the plates to the saddle blocks.

10. A baffle for tubular boilers, stills and the like comprising a plurality of relatively thin metal plates disposed in a plane sub-

stantially parallel to that of the tubes and having their lateral edge portions in contact with each other to form a continuous baffle, saddle blocks mounted on the tubes and means for attaching the plates to the saddle 15 blocks, said plates being free to individually expand and contract.

Signed at Pittsburgh, Pa., this 14th day of March, 1927.

CHARLES P. MILLS.
